UNITED STATES PATENT OFFICE

131,823

DESIGN FOR AN EYECUP BOTTLE

Roy Peacock, Chicago, Ill.

Application February 26, 1941, Serial No. 99,226

Term of patent 14 years

To all whom it may concern:

Be it known that I, Roy Peacock, a citizen of the United States, residing at Chicago, in the county of Cook and State of Illinois, have invented a new, original, and ornamental Design for an Eyecup Bottle, of which the following is a specification, reference being had to the accompanying drawing, forming part thereof.

Fig. 1 is a front elevational view of an eyecup bottle showing my new design.

Fig. 2 is a side elevational view thereof.

Fig. 3 is a top plan view of an eyecup bottle.

Fig. 4 is a longitudinal sectional view taken through the principal axis.

The characteristic features of my design reside in the portions shown in full lines.

I claim:

The ornamental design for an eyecup bottle, as shown and described.

ROY PEACOCK.
